UNITED STATES PATENT OFFICE.

JAMES F. WELLS AND HARRY B. HARLOW, OF ALTON, ILLINOIS, ASSIGNEES TO JOHN H. McPIKE, OF ALTON, ILLINOIS.

BOX-STRIPPING MACHINE.

1,046,355.

Specification of Letters Patent. Patented Dec. 3, 1912.

Application filed May 11, 1911. Serial No. 626,541.

To all whom it may concern:

Be it known that we, JAMES F. WELLS and HARRY B. HARLOW, citizens of the United States, residing at Alton, Illinois, 5 have invented a certain new and useful Improvement in Box-Stripping Machines, of which the following is a full, clear, and exact description, such as will enable others skilled in the art to which it appertains to 10 make and use the same, reference being had to the accompanying drawings, forming part of this specification, in which—

Figure 1 is a side view of as much of our improved machine as necessary to illustrate 15 the improved parts. Fig. 2 is a plan view showing simply the parts on and below the conveyer table. Fig. 3 is an elevational view of certain parts above the conveyer table. Fig. 4 is a side view of the same 20 parts illustrated in Fig. 3. Figs. 5, 6, 7, 8, 9, illustrate details of construction.

This improvement relates to machines for applying strips to paper boxes intended to be used more especially for shipping purposes.

25 The machine to be described is intended to apply an adhesive strip to the corner of a box, which box is presented to the applying mechanism in a folded form. The boxes are folded flat so that the four sides are 30 formed in one sheet, and the edges of the sheet are brought into proximity in order that the adhesive strip may be applied thereto by our improved machine. The sheet forming the box is properly slotted to 35 form the flaps to be folded and engaged so as to form a closure for each end of the boxes.

The object of our invention is to provide a simple machine for applying adhesive strips to the boxes of the character 40 described and to cut off strips to proper length for the different sizes of boxes.

Other objects of our invention will appear in the course of our description, and be pointed out in the accompanying claims.

45 We have shown our improvement as used in connection with a paper box feeding means; but it should be understood that the strip applying means could be used in other connections, and that the feeding mechanism to be described could also be used independently of the strip applying means if desired. We do not, therefore, desire our improvement to be confined to the art of manufacturing paper boxes.

55 Referring to the drawings, 1 indicates

generally a conveyer table which is comprised of a top 2, sides 3 and legs 4. At one side of the table 1 and journaled within the sides 3 is a main shaft 5, which shaft is driven from any suitable means by a pulley 6 fastened at one end. This shaft 5 extends transversely of the table, and has a series of sprocket wheels 7, 8, 9 and 10 keyed thereto. Sprocket wheel 7 is applied to the shaft 5 outside the sides 3 of the table 60 1, and sprocket wheels 8, 9 and 10 are distributed across the table between the side walls 3 thereof so that sprocket 8 is near one wall, sprocket 10 near the other and sprocket 9 substantially centrally located between the 65 two. On the opposite end of the table from shaft 5 is suitably mounted the shaft 11 having sprocket wheels 12, 13 and 14 fastened thereon, which are positioned opposite sprockets 8, 9 and 10 respectively. A conveyer chain 15 is passed from sprocket 8 to sprocket 12 and through a groove 16 within the table top 2. Similarly a sprocket chain 17 is passed between sprocket gears 9 and 18 within the groove 18 in the table top, also 70 a chain 19 is passed between sprockets 10 and 14 and through a groove 20. On the table top at suitable intervals a strip 21 is attached by screws or otherwise to chains 15, 17 and 19, which strip 21 bears on the 75 top of the table to pass longitudinally over the table. A guide block 22 is adjustably connected to strip 21, said block being formed with a groove having opposite projections 23, adapted to engage in opposite under-cut grooves 24 in the sides of the strip 21 so that the block may slide along the strip 21, and be held in adjusted position by means of set screws 25.

80 Mounted on the outside of the table side 3 is a stud shaft 26 in any suitable manner. This stud shaft has a sleeve 27 rotatably and loosely mounted thereon, and three sprockets 28, 29 and 30 adjustably fixed to the sleeve, the sprocket 28 being positioned 85 opposite sprocket 7 on the shaft 5. Sprockets 7 and 28 are connected by means of a chain 31. 32 is a second stud shaft upon which is rotatably mounted a sleeve 33 having sprockets 34 and 35 adjustably fixed 90 thereto. Sprockets 29 and 34 are connected by means of a chain 36, and sprockets 30 and 35 are connected by means of a chain 37. Brackets 38 are bolted to the side 3 intermediate the shafts 26, and 32 to form a support 95 100 105 110

for a guard strip 39 positioned under chains 36 and 37. Chain 36 is provided with a tripping block 40, and chain 37 with a tripping block 41. The length of the chains 36 and 37 is equal to the length of chains 15, 17 and 19 between an adjacent pair of conveyer strips 21, and sprocket gears 7, 8, 9 and 10 are all the same size the purpose of which arrangement will be hereinafter fully set forth.

Attached to one of the sides 3 is a hanger and support 42 in the shape of a substantially semicircular cast piece, the arms of which 43 and 44 form a support for a shaft 45 extending therebetween. Arm 44 of the bracket 42 is yoke shaped to form separate members 46 and 47, having journals 48 and 49, for the shaft 45, and between these journal bearings is mounted on the shaft 45 a roll 50. This roll coöperates with a roll 51 adjustably mounted within the table top 2 to be adjusted toward and from the roll 50. The shaft 45 is driven from shaft 5 by means of a crossed belt 52.

In the upper portion of the hanger 42 is mounted in bearings 53 and 54 an oscillatory shaft 55. This shaft is moved in one direction through an arm 56 having a plate member 57 attached at one end and extending below the top of table 2 to one side thereof to be engaged by the stop 40 on chain 36, and is moved in the opposite direction through a spiral spring 57^a fastened to the shaft 55 at one end and to the bearing 54 at the other. At one end of the shaft 55, opposite the arm 56, is also loosely mounted a guide arm 59. This arm has two extensions 60 and 61 from the shaft 55, and is provided with a curved guide way 62 through which the strip to be pasted is adapted to pass and the lower portion of this curved guide-way extends to a point in proximity to the roll 50 when moved about the shaft 55. Upon the top member 60 of arm 59 is slidably mounted a clamp block 63, which moves in guideways 64 with one end of the same in proximity to the guide way 62, and the other extending over the shaft 55 to be engaged by a lug 65, which lug is mounted on collar 66 fast on the shaft 55. The clamp block 63 is provided with a stop 67 to engage with guide way 64, and a spring 68 is fastened to the side of the slide block and to a pin on extension 60 to normally cause the clamp block to remain in retracted position away from the adhesive strip in the guide way 62. The arm 59 is formed with a divided hub to embrace the sides of the collar 66 on the shaft 55 (see Fig. 4). A lever 69 is rigidly fixed at one end to the shaft 55 adjacent the outer hub of the arm 59 and the forward end 70 of said lever is provided with heads against which the extension 60 of the arm 59 is adapted to engage. The overhanging arm support 42 is also provided with a bearing

71 for a stud 72 upon which is rotatably mounted a strip supporting reel 73. This reel is prevented from too free rotation by means of a collar 74 engaging with a spring 75 the tension of which is adjusted through a well known means 76. Also clamped in position on the stud 72 is an arm 77 having a guide roll 78 at its extremity. The guide roll 78 is rotatably located upon a stud 79 to which is attached a link 80 extending downwardly to one side of stud 72, and provided at its extremity with a stud 81 upon which a guide roll 82 is rotatably mounted.

A brace 83 is attached at 84 to the overhanging arm support 42, and forms a bearing to which the stud 81 is clamped. This brace 83 is also to form a bearing for a stud 85 upon which a fixed guide roll 86 is mounted, and said brace 83 also acts as a support for a sponge or other adhesive applying device 87. Brace 83 is provided with a projecting stop member 87' which is adapted to be engaged with the clamp block 63 when moved upward about the shaft 55.

The roll or strip of paper to be attached to the box is mounted on the reel 73, and the paper placed under roll 86 against the adhesive applying device 87, up over roll 78, down against a guide roll 82 and through a guide way 62 to the end thereof.

The overhanging arm 42 adjacent the roll 50 is provided with extensions 88 within which is journaled a shaft 89 extending through the oppositely arranged bearing 90 in the extension 88. This shaft has a collar 91 attached, and a spiral spring 92 is mounted on the shaft 89 and between the bearing 90 and collar 91 to normally hold a tripping collar 93 in engagement with bearing 90 on the side opposite from the spring 92.

Coöperating with the tripping collar 93 is a tripping lever 94 pivoted at 95 to a suitable bracket support 96, the end of the lever 94 being shaped to extend within the path of movement of block 41 on chain 37. A tension spring 97 is fastened to the end of the lever 94 and to table top 2. The end of lever 94 is adapted to be positioned in front of the side 93' of tripping collar 93 to hold the spindle 89 in dotted line position of Fig. 5 against the action of the spring 92.

The portion of the overhanging arm 42, which is adjacent the side 3 of the table, is provided with a projecting cast bracket 98, in the extremity of which is journaled shaft 89. Fixed to this cast bracket is an additional bracket support 99 to which is attached a pawl carrying plate 100 having a curved pawl 101 pivoted thereto at 102, the curved end of the pawl 103 engaging normally a lug 104 on the plate 100. The pawl 101 has an opening 105. A flat spring 106 is attached to the plate 100 and bears against the side of the pawl 101 to retain the pawl in engagement with the lug 104. A pin 107

80

90

95

100

105

115

120

125

130

extends from the shaft 89 and passes adjacent the lug 104 so that as the shaft is moved longitudinally the pin will engage the pawl 101 to move it laterally against the spring 106. When the shaft 89 moves in the opposite direction the pin 107 rides along the curved surface of the pawl 101 until it reaches the opening 105 when it drops through this opening to its normal position against the lug 104. By this operation, during the oscillation of the shaft 89, in one direction, it is moved laterally to operate the knife to be described.

Adjacent the roll 50 and in advance thereof is positioned on shaft 89 a block 108 to which a cutting blade 109, with a serrated cutting edge, is fastened. This blade coacts with a stationary cutter 109' attached to members 46 and 47. In advance of the cutter is positioned a presser 110 which is supported in any suitable manner from the arm 44, as by a bracket 111. On top of the presser 110, and extending adjacent the stationary cutter 109' is positioned a strip guard or deflecting piece 112 preferably in the form of U-shaped piece of wire with several spring wires bearing against it as shown in Fig. 9.

Adjacent the arm 43 as attached to the top of the table 1 is a bracket 113 to which is pivoted at 114 a lever 115 of crescent shape, one end of the lever being in the path of movement of lever 56, and the other end in position to engage the side 93' of collar 93.

An air cushion 116 is connected to lever 56 and to the fixed arm 42 in any suitable manner.

The operation of our machine will now be described.

A paper box being properly slotted and folded is placed in position against the strip 21 and guide 22, the box being folded flat with the adjacent edges to be united, by an adhesive strip, on top. The boxes are advanced by the conveyer or feeding mechanism, between the rolls 50 and 51, and simultaneously through operation of the arm 56 the shaft 55 is oscillated to move the guide way 62 into proximity to the roll 50. A portion of the adhesive strip extends from the guide 62 under the roll 50 and is applied to the box across the adjacent ununited edges thereof. At the proper time, that is, when the end of the box or any position desired is passing under the roll, the knife 109 is moved into engagement with the strip to sever it by means of a shear cut due to the combined oscillatory and lateral movement of the shaft 89. When boxes of different lengths are acted upon the strips of adhesive material are necessarily of different lengths and the timing of the strip guiding means and cutter must be changed. To provide for this the sprocket gears 28, 29 and 30 are made adjustable, and the time of

operation of the tripping blocks 40 and 41 can be controlled in this manner. The strip guide 62 is moved in one direction by the action of the arm 69 against the under side of the extension 60, that is, they move the 70 guide to its upper position against the stop 87'. The arm 69 engages the lower extension 61 to move the arm 59 in the opposite direction to position the lower end of the strip guide 62 beneath the shaft 89 adjacent 75 the roll 50, and when so positioned, the end of said guide strip bears upon and depresses the deflecting member 112. During this latter movement, and before the adjacent screw 70 engages the extension 61, the lug 65 acts upon the slide block 63 to cause its end to engage the adhesive strip passing through the guide 62 to clamp it within the guide. Afterward the screw 70 engages the extension 61 to move the guide 62 and thereby feed a portion of adhesive strip from the reel 73. This movement of the shaft 55 is produced by means of lug 40 engaging arm 56. The opposite movement of shaft 55 is produced by the spring 57' and the first action is to move the lug 65 releasing the clamp block 63 and then allowing the end of the arm 69 to engage the bottom of the extension 60 to move the guide way 62 without pulling on the adhesive strip, the strip 90 not being fastened in this movement.

The shaft 89 operating the cutter 109 is actuated by means of lug 40 striking lever 56 which in turn engages and moves lever 115, and this lever, by bearing against the collar 93, moves the shaft 89 laterally so that the cutter 109 is in cutting position, the trip 94 being moved by the spring 97 to engage and hold the collar 93 with the shaft 89, as shown in dotted line position 100 in Fig. 5. The lug 41, on chain 37, strikes the tripping lever 94 to move it against the action of the spring 97, which allows the shaft 89 to move laterally, due to the action of the spring 92. During this lateral movement the pin 107 on the shaft rides on the pawl 101 to oscillate the shaft 89, to a slight extent. The cutter 109 is thereby given both a lateral and an oscillatory movement and the lateral movement is discontinued by the 115 pin 107 falling through the slot 105 in the pawl 101. When the strip guide 62 is moved downwardly to its limit of movement, its lower end engages and depresses the deflecting piece 112 and after the cutter 109 has 120 acted to cut the gummed strip of tape and the strip guide moves upwardly, the pressure upon the deflecting piece 112 is released and the same moves upwardly a slight distance, thereby elevating the end of the tape 125 and straightening out the end of the tape which has a tendency to bend downward and to lap over the edge of the plate 110 when the knife or cutter moves downwardly and engages said tape. Thus the severed 130

end of the tape projecting from the lower end of the strip guide is elevated slightly and in this position is ready to move forwardly in the next operation. The air cushion connected with the lever 56 prevents the spring 57 from returning the guide way 62 to its upper position in too quick and abrupt a manner.

We are aware that minor changes may be made in the construction, arrangement and combination of the various elements of our improved machine without departing from the spirit of our invention, the scope of which is set forth in the accompanying claims.

15. We claim:

1. In a device of the character described, a box feeding means, a strip applying means, a strip severing device, means for operating the feeding means and means for operating the strip applying means and severing device, said latter means being timed to move the strip applying means adjacent the box as the box is passing and to sever the strip before the box has passed the strip applying device.

2. In a device of the character described, a table, a conveyer operating to move over the table, a bracket supported by the table, 30 a strip guiding means pivoted in said bracket, a feeding roll mounted within the bracket and means for automatically moving the strip guiding means adjacent the feeding roll and retracting the guiding means.

3. In a device of the character described, an operating shaft, a feeding means operated from said shaft, a strip applying and guiding means, means for moving said strip applying and guiding means adjacent the feeding means, means for severing the strip and means, comprising continuous chains having tripping blocks thereon, for operating to move the strip applying means and 45 strip severing means.

4. In a device of the character described, a continuous conveyer having guide strips mounted thereon at intervals, a feed roller operating above the conveyer, a strip feeding and applying device movable into position adjacent the feed roller and above the conveyer, a strip severing device and means for moving the strip applying device and operating the strip severing device, comprising chains having tripping blocks thereon, the length of said chains being the same as the length of the conveyer between the guiding strips.

5. In a device of the character described, 60 a table, a continuous conveyer traveling over said table, an operating shaft for said conveyer, a strip applying device mounted above said conveyer, means for moving said strip applying device adjacent a feed roll and two coöoperating feed rolls one above

and the other below the conveyer, the latter being adjustably mounted.

6. In a device of the character described, a table, a continuous conveyer having guide strips mounted at intervals thereon positioned to move over the table, an operating shaft therefor, a strip applying device mounted above the conveyer, a severing device and means for operating said strip applying device and strip severing device comprising adjustable sprocket gears, chains operated on said sprocket gears and tripping blocks positioned on said chains, said chains equaling in length the length of the conveyer between adjacent guiding strips.

7. In a device of the character described, a table, a continuous conveyer having guide strips mounted at intervals thereon positioned to move over the table, an operating shaft therefor, a strip applying device 85 mounted above the conveyer, a guide block adjustably mounted on the guiding strips, a severing device and means for operating said strip applying device and strip severing device comprising adjustable sprocket gears, chains operated on said sprocket gears and tripping blocks positioned on said chains, said chains equaling in length the length of the conveyer between the adjacent guiding strips.

8. In a device of the character described, a table, a bracket mounted thereon, a shaft in said bracket, a strip applying device loosely mounted on said shaft and means for operating said strip applying device 100 comprising a lever fast on the shaft adapted to engage the strip applying device to move it in both directions.

9. In a device of the character described, a table, a bracket mounted thereon, a shaft 105 journaled in the bracket, a strip feeding and applying device loosely mounted on said shaft, a lever fast on the shaft to operate the strip applying device, a clamp block mounted on the strip applying device 110 and means on the shaft for moving the clamp block to clamp the strip within the strip applying device.

10. In a device of the character described, a table, a bracket mounted thereon, a shaft 115 rotatably mounted on the bracket, a strip guiding and applying device loosely mounted on said shaft comprising two arm extensions from the shaft and a guide way at the extremity thereof and an arm fixed to 120 the shaft positioned between the arm extensions to engage with either and move the strip applying device when the shaft is oscillated.

11. In a device of the character described, 125 a table, a bracket mounted thereon, a shaft rotatably mounted on the bracket, a feed roll mounted on the bracket, a support for a roll of tape rotatably mounted on the bracket, a tape or strip feeding and apply- 130

ing device loosely mounted on the shaft comprising a guide way for the strip, means for clamping the strip within the guide way and a lever fast on the shaft adapted to engage 5 the strip applying device to move the same in opposite directions.

12. In a device of the character described, a bracket, a shaft journaled on the bracket, a strip applying device loosely mounted on 10 the shaft comprising arms extending from the shaft and a curved strip carrying guide connected to the ends of the arms; a clamping block slidably mounted on one of the arms, a lug fast on the shaft adapted to 15 operate said clamp block and an arm fast on the shaft adapted to operate the strip applying device in opposite directions.

13. In a device of the character described, a bracket, a shaft journaled on the bracket, 20 a strip applying device loosely mounted on the shaft comprising arms extending from the shaft and a curved strip carrying guide connected to the ends of the arms, a clamping block slidably mounted on one of the 25 arms, a lug fast on the shaft adapted to operate said clamp block, an arm fast on the shaft adapted to operate the strip applying device in opposite directions and a stop 30 to engage the strip applying device to hold it in normal position.

14. In a device of the character described, a table, a bracket supported thereon, a shaft journaled on the bracket, a strip applying 35 guide loosely mounted on the shaft, an arm fixed to the shaft adapted to move the strip applying guide in opposite directions, a lever on the shaft and a tripping block operating below the table to move the lever and thereby the strip applying guide.

40 15. In a device of the character described, a table, a bracket mounted on the table, a shaft journaled on the bracket, a strip applying device loosely mounted on the shaft, a lever fixed on the shaft adapted to move 45 the strip applying device in opposite directions, a spiral spring fast to the shaft at one end and to a fixed part at the other, a lever

on the shaft and means for operating the lever.

16. In a device of the character described, 50 a table, a bracket mounted on the table, a feed roll mounted on the bracket, a presser and strip guide positioned in front of the roll, a shaft journaled on the bracket, a strip applying device loosely mounted on the 55 shaft adapted to be moved adjacent the feed roll and above the presser and means fast on the shaft to operate the strip applying device.

17. In a device of the character described, 60 a table, a bracket mounted on the table, a shaft journaled on the bracket, a strip applying device loosely mounted on the shaft, an arm for operating the strip applying device in opposite directions, a lever on the 65 shaft, an air cushion attached to the lever and means for oscillating the lever to move the strip applying device.

18. In a device of the character described, 70 a table, a feed roll, a strip applying device, a strip severing device, a presser and a strip elevating means comprising a resilient member attached to the presser.

19. In a box strip machine, a box conveyer, a strip-applying means mounted for 75 swinging movement above the conveyer and adapted to move the end of a gummed strip into contact with the surface of the box, a strip-severing device, means for operating 80 said severing device, means for operating the conveyer and means for actuating the strip-applying means, said actuating means being timed to move the applying means adjacent the box at the time said box is passing beneath the applying means. 85

In testimony whereof we hereunto affix our signatures in the presence of two witnesses, this 6th day of May, 1911.
